UNITED STATES PATENT OFFICE.

BERNARD W. GATES, OF WASHINGTON, DISTRICT OF COLUMBIA.

STRUCTURAL IMITATION OF NATURAL OBJECTS.

1,150,027.

Specification of Letters Patent. Patented Aug. 17, 1915.

Application filed August 19, 1914. Serial No. 857,509.

To all whom it may concern:

Be it known that I, BERNARD W. GATES, a citizen of the United States, residing at Washington, in the District of Columbia, have invented certain new and useful Improvements in Structural Imitation of Natural Objects, of which the following is a specification.

My invention relates to improvements in ornamental objects and more particularly to structural imitation of natural objects such as twigs, reeds, branches, vines, stems, etc., together with the method of making the same.

15 The object of my invention is to provide a structure which is simple in construction, readily manipulated, neat and attractive in appearance, and which can be manufactured at a relatively low cost.

20 To these and other ends, the nature of which will be readily understood as the invention is hereinafter disclosed, said invention consists in the improved construction and combination of parts and the method of 25 construction of the same hereinafter fully described, illustrated in the accompanying drawings, and more particularly pointed out in the appended claims.

30 In the accompanying drawings, in which similar reference characters indicate similar parts in each of the views, Figure 1 is a perspective view of one form of the invention representing a portion of a vine, said view also showing twigs or branches secured thereto, parts being broken away to show 35 more clearly the manner in which the twigs or branches are secured in position. Fig. 2 is a cross-sectional view of the structure of Fig. 1. Fig. 3 is a perspective view showing 40 the invention in the form of the stem of a flower. Fig. 4 is a cross-sectional view of the stem of Fig. 3. Fig. 5 is a detail sectional view showing a different way in which the twigs or branches may be secured 45 to a vine. Fig. 6 is a perspective view of the structure of Fig. 1 showing a portion in its untwisted state.

50 The present invention employs approximately two elements in its construction, viz., paper and a supporting member which is sufficiently rigid to provide a proper support, but which is preferably non-resilient, and which may be somewhat ductile in character.

55 The paper element is formed twisted and

preferably of a plurality of such twisted portions, these portions being simultaneously twisted with the supporting member, the latter being in the form of one or more wires which are inclosed during the twisting 60 action of the strands.

In the drawings, 10 designates the paper elements, formed of a plurality of the paper members 10^a. These members which constitute a sheath, may be either twisted or crinkled, but when formed into the finished product they are twisted together. The support or core is indicated as in the form of a wire 11, somewhat ductile in order that when the article is adjusted to the desired 70 shape it will retain that shape, this being a particular advantage where the article is employed in festooning, etc.

By reason of the twisting together of the members 10^a, I am able to provide for the 75 ready attachment of the structures intended to form twigs, branches, leaves, etc., which may be employed, since it is necessary only that the particular section of the article which is to receive the stem be simply un- 80 twisted slightly to present an orifice or pocket enabling the twig or the like to be inserted between the outlines within the interior of the article, after which the parts are again twisted, leaving the surface unaltered 85 and giving the appearance of the twig or branch naturally springing from the vine. Better results will be obtained if the free ends of the twigs, leaves, etc., are previously 90 treated with an adhesive.

In the drawings, the stem of the twig or leaf is indicated at 12, including a wire core 12^a, the inner end of said stem being infolded within the twisted portions 10^a, as more particularly shown in Fig. 1. This particular means of securing the twig is sufficient for normal conditions and service. If greater security is desired, the wire core 12^a may be formed in the shape of a small hook 95 which can be slipped over the core or support 11 while the paper element is untwisted, the re-twisting substantially locking the hook against disengagement.

As will be obvious, the twisting of the crinkled or twisted members, if somewhat loose, will provide for an uneven surface, so that if paper of the proper color is employed a very close imitation of the natural vine can be produced and in a form which will enable the auxiliary branches, etc., to be 110

readily secured in position without materially affecting the twisted relation of the parts.

If the members 10^a be tightly twisted together about a single supporting member, as exhibited in Fig. 3, a close approximation of a stem of a flower or the like is produced, the tight twisting giving the smoother appearance and insuring greater rigidity of the stem. When this form is employed, suitable incisions are made in the paper with an awl or the like, whereupon smaller stems 13 of leaves, etc., having been previously treated with an adhesive, may be inserted in the said incisions.

An important feature of novelty of this invention and one which, so far as known, differentiates it from the art as understood is that one main stem may be utilized in the construction of many different types of vines or plants, so that when used, either for ornamental or decorative purposes, it will only be necessary for the decorator to have in stock numerous designs of leaves, branches and the like in order to produce an accurate simulation of the plant desired. This highly advantageous and practical result is secured by the novel manner of assembling the stems of the leaves with the main stem or parent stock, whereby with but slight labor and no danger of injury, the leaves simulating one type of vine or flower may readily be removed and substituted by other leaves imitating an entirely different species of plant. Whether the ends of the leaf stems are held assembled with the parent stem merely by the gripping action produced by the contractile action of the sheath members, or the latter assisted by the employment of an adhesive on the leaf stems is immaterial as regards the ease with

which the leaves may be detached from or combined with the main stem in the production of any type of plant desired.

Since the paper employed is comparatively inexpensive, as are the core elements, it will be readily understood that the structure can be manufactured at a low cost, the apparatus employed being of a simple type, or the structure may be formed manually in a simple manner.

While I have shown and described ways in which the invention may be carried out, it will be readily understood that the same may be varied and changed to meet the various exigencies of use, and I desire to be understood as reserving the right to make such changes or modifications therein as may be found necessary to meet such conditions in so far as the same may fall within the spirit and scope of the invention as expressed in the accompanying claims.

Having thus described my invention, what I claim as new is:

1. An artificial vine or reed composed of a plurality of twisted strands of paper twisted together spirally about a central core of pliable non-resilient metallic wire.
2. An artificial vine or reed composed of a plurality of twisted strands of crumpled paper twisted together spirally about a central core of pliable non-resilient metallic wire, and auxiliary parts secured to said vine, the stems of said parts being held between contiguous surfaces of said twisted strands.

In testimony whereof I hereunto affix my signature in presence of two witnesses.

BERNARD W. GATES.
